Patented Sept. 21, 1976

241,547

COMBINED FIREPLACE AND HEATING STOVE

Edwin S. F. Francis, 3930 Hobbs St.,
Victoria, British Columbia, Canada

Filed Aug. 7, 1975, Ser. No. 602,746

Term of patent 14 years

Int. Cl. D23—03

U.S. Cl. D23—97

FIG. 1

FIG. 2

FIG. 3

FIG. 4

FIG. 5

FIG. 1 is a perspective view of a combined fireplace and heating stove showing my new design;

FIG. 2 is a front elevational view thereof;

FIG. 3 is a side elevational view thereof;

FIG. 4 is a bottom plan view thereof; and

FIG. 5 is a rear elevational view thereof.

The view of the side not shown is the same as the illustration in FIG. 3.

I claim:

The ornamental design for a combined fireplace and heating stove, as shown and described.
